UNITED STATES PATENT OFFICE.

ERNEST S. THOMPSON, OF DETROIT, MICHIGAN.

DISK-RECORD-REPLAYING DEVICE.

1,376,177.

Specification of Letters Patent. Patented Apr. 26, 1921.

Application filed February 26, 1917, Serial No. 150,937. Renewed April 24, 1918. Serial No. 230,302.

To all whom it may concern:

Be it known that I, ERNEST S. THOMPSON, a citizen of the United States of America, residing at Detroit, in the county of Wayne and State of Michigan, have invented certain new and useful Improvements in Disk-Record-Replaying Devices, of which the following is a specification, reference being had therein to the accompanying drawings.

This invention relates to sound producing devices and refers more particularly to the provision of mechanism for automatically replaying disk records or the like.

Among the objects of the invention are to provide a construction which can be attached to phonographs or other disk record playing devices so as to automatically replay the record two or more times; to provide a construction which can be used with the record playing device, either as standard equipment or as an attachment without changing the construction of the other mechanism; to so construct and arrange the replaying device that it can be set to take care of records of different sizes and the shifting of the clutch is preferably governed by movement of the needle sounding arm; to provide a construction whereby the needle at the end of the playing of the record is automatically raised, reversed to its initial position and again let down on the record; to provide a construction in which the replaying mechanism is operated from a drive connection to the record plate or other moving part of the record playing device, and in general to provide a new and improved construction of the character above referred to.

The invention also resides in the novel shifting and locking mechanisms and such other details of construction and arrangements and combinations of parts as will more fully hereinafter appear.

In the drawings:

Figure 1 is a fragmentary perspective view, partly broken away, showing my device in use;

Fig. 2 is a fragmentary top plan view partly in section of the replaying mechanism, the arm being adjusted substantially toward its inner position;

Fig. 3 is a vertical section on the line $\alpha-\alpha$ Fig. 2;

Fig. 4 is a side elevational view of the lifting cam mechanism; and

Fig. 5 is a vertical section on the line $y-y$ of Fig. 2.

Describing in detail the embodiment of my invention shown in the drawings, A designates the record carrying plate revolvably mounted on a spindle B so as to rotate the record C when the latter is placed upon the plate. The usual needle D operates in the grooves C' of the record and as the record is played the disk E carrying the needle is shifted toward the center from the outer edge C² to the inner end of the groove C³. The needle carrying disk is carried by sounding arm F pivotally mounted on the upper surface of the stand or supporting member G. The latter also carries the base H of the replaying mechanism, the detail construction and operation of which mechanism is as follows: Projecting upward from the base H is a stationary post I upon which is revolvably mounted a sleeve J carrying an arm J' which at its outer end is provided with a pivoted seat J² fitting under the needle carrying arm F, the arrangement being such that as the needle carrying arm swings from side to side the sleeve J will be rotated about the post I. Surrounding the lower end of the sleeve J is a cam sleeve T and a worm gear L meshing with a worm shaft M revolvably mounted in the blocks M' and M². This worm shaft at its inner end has a bevel gear N meshing with an idler gear N' which in turn meshes with the bevel gear N² loosely mounted on the shaft O. The drive connection to the replaying mechanism is obtained through the shaft O which extends through the bearing O' and at its inner end has a bevel pinion O² meshing with the bevel gear O³ on the record carrying plate A. It is to be understood, however, that the invention in its broader aspects is not limited to the particular shaft drive shown.

Splined to the outer end of the shaft O is a dog clutch P having at its opposite ends locking lugs P' and P² so that when the clutch is shifted to the position shown in Fig. 3 it will lock the pinion N² to the shaft O and drive the worm shaft M through the gears N², N' and N. When, however, it is shifted to the position shown in Fig. 2 the worm shaft will be discon-

nected from the drive shaft O, while upon further movement to the right the lugs P² will be engaged in the recesses in the gear N and thus connect the worm shaft M direct to the shaft O and cause it to rotate in the opposite direction from that first mentioned.

The arrangement of parts is such that when the needle reaches the groove C³ the sleeve J will be raised so as to lift the needle away from the record, after which the arm F will be swung back to carry the needle to a position near the outer edge of the record. The needle will then be lowered automatically into contact with the record and permitted to again move across the face of the record in the usual manner.

A suitable gear shifter is employed, having a yoke Q¹ engaging the clutch P and an arm Q² engageable with a ball friction lock R and a pair of arms Q³ and Q⁴ extending into the path of the lugs L' and L² carried on the worm wheel L. The shifter also has an upwardly extending arm Q⁵ positioned in the path of an adjustable stop R' carried by a rod R² secured to the arm J' by a set screw R³. The ball lock R is mounted within a housing S and normally pressed upward by a spring S'. When the parts are in the position shown in Figs. 1 and 2 the clutch is in neutral and the arm Q² is held part way up on the ball lock R by means of the lug L'. The parts remain in this position until the needle D has traveled across the record to the inner groove C³. When it reaches this groove the adjustable stop R' hits against the arm Q⁵ of the gear shifter and rocks the latter about its pivot W so as to carry the arm Q² onto the opposite side of the friction lock R in which position the worm shaft M is clutched to the shaft O through the gears N, N' and N². This causes the worm wheel L to rotate in the direction indicated by the arrow in Fig. 2, thus carrying the pin T' beneath the inclined surface T² of the sleeve T and raising the latter and the sleeve J so as to withdraw the needle from engagement with the record and hold it clear of the latter. As the worm wheel continues to rotate the pin T' will finally abut against the shoulder T³ and thus carry the sleeve and tone arm back toward the outer side of the record. After the tone arm has reached the desired position at the outer edge of the record the lug L² striking against the arm Q⁴ of the gear shifter will rock the latter so as to swing the arm Q² upon the opposite side of the center of the ball R where it is free to move down the ball and move the clutch to engage its pins P² with the recesses in the gear N and thus couple the worm shaft M directly to the shaft O. This will cause the worm wheel L to rotate in the opposite direction until its pin L' hits against the arm Q³ and carries the arm Q² of the gear shifter

up on to the ball R. As soon, however, as this arm has ridden up on to the ball a sufficient distance to move the clutch into neutral position, the drive connection to the member L will be disconnected and thus by stopping the movement of the pin L' will lock the parts in neutral position.

It will, of course, be understood that this operation will be repeated as long as the record plate is rotated. To permit records of different sizes being used the sleeve T is provided with a set screw V which can be engaged with various notches V' in the sleeve J. While I have shown the invention applied to a construction having a sounding arm which lifts up throughout substantially its entire length, it could, of course, be employed with constructions in which merely the outer end of the arm is raised and with various other constructions, also various changes in the details of construction and arrangements and combinations made within the scope of my invention.

What I claim as my invention is:

1. In a playing device for spirally grooved disk records, the combination with a rotatable record-carrying member, of a needle-carrying member adapted to be advanced across the record when its needle is engaged with the groove of a record and said record-carrying member rotated, a lifting member for said needle-carrying member, a drive connection between said record-carrying member and lifting member, a reversible clutch mechanism for throwing said drive connection into operation in either direction, means controlled by movement of the needle-carrying member for throwing the clutch into operation so as to operate the drive connection in one direction, and means controlled by movement of the drive connection for throwing the clutch to operate the drive connection in the opposite direction.

2. In a playing device for spirally grooved disk records, the combination with a rotatable record-carrying member, of a needle-carrying member adapted to be advanced across the record when its needle is engaged with the groove of a record and said record-carrying member rotated, a lifting member for said needle-carrying member, a drive connection between said record-carrying member and lifting member, said drive connection comprising a rotatable shaft, a clutch for connecting said shaft to be driven from the record-carrying member in either direction, and an automatic clutch shifter comprising a plate and an inclined surface over which the plate is moved to automatically shift the clutch.

3. In a playing device for spirally grooved disk records, the combination with a rotatable record carrying member, of a needle carrying member adapted to be advanced

across the record when its needle is engaged 5
with the groove of a record and said record
carrying member rotated, a lifting member
for said needle carrying member, a post on
which said lifting member is slidably en-
gaged and a member rotative axially of said
post having a cam engagement with said
lifting member for automatically raising the
latter upon the needle-carrying member
10 reaching its inner limit of travel.

4. In a playing device for spirally grooved
disk records, the combination with a rota-
table record carrying member, of a needle
carrying member adapted to be advanced

15 across the record when its needle is engaged
with the groove of a record and said record
carrying member rotated, a lifting member
for said needle carrying member, mechanism
for driving said lifting member, a clutch

20 controlling the drive to said member, a
shifter for said clutch, and means carried by
said driving member engageable in a certain
position thereof with the shifter to actuate
the clutch.

25 5. In a playing device for spirally grooved
disk records, the combination with a rota-
table record carrying member, of a needle
carrying member adapted to be advanced
across the record when its needle is engaged

with the groove of a record and said record 30
carrying member rotated, a lifting member
for said needle carrying member, drive
mechanism for said lifting member includ-
ing a clutch mechanism for establishing the
drive in either direction, means controlled 35
by movement of the needle carrying member
for controlling the clutch into operation so
as to operate the drive connection in one di-
rection, and means controlled by movement
of the drive connection for throwing the 40
clutch to operate the drive connection in the
opposite direction.

6. In a playing device for spirally grooved
disk records, the combination with a rota-
table record carrying member, of a needle 45
carrying member adapted to be advanced
across the record when its needle is engaged
with the groove of a record and said record
carrying member rotated, a lifting member
for said needle carrying member, drive 50
mechanism for said lifting member includ-
ing a clutch for establishing the drive in
either direction, and an automatic clutch
shifter comprising a plate, and an inclined
surface over which the plate is moved to au- 55
tomatically shift the clutch.

In testimony whereof I affix my signature.
ERNEST S. THOMPSON.
